UNITED STATES PATENT OFFICE.

JOSEPH P. URBAN, OF DETROIT, MICHIGAN.

GARBAGE-RECEPTACLE.

1,371,007.

Specification of Letters Patent.

Patented Mar. 8, 1921.

Application filed June 11, 1920. Serial No. 388,126.

To all whom it may concern:

Be it known that I, JOSEPH P. URBAN, a citizen of the United States of America, residing at Detroit, in the county of Wayne 5 and State of Michigan, have invented certain new and useful Improvements in Garbage-Receptacles, of which the following is a specification, reference being had therein to the accompanying drawings.

10 This invention relates to that class of garbage receptacles which is exemplified by Patent 956,454, granted April 26, 1910, and the object of my invention is to improve the garbage receptacle in the following partic- 15 ulars.

First, the upper portion of the garbage receptacle is made separate from the lower portion thereof and connected to the lower portion of the receptacle so that it may be 20 removed, when injured, thus obviating the necessity of completely discarding the receptacle should its upper portion be broken or materially injured. With this class of garbage receptacles the upper portions there- 25 of are exposed to more wear and tear than the lower portions thereof due to garbage removing implements contacting therewith and small garbage receptacles or utensils being knocked against the top portion of the 30 large receptacle to remove the garbage from the small receptacle. This wear and tear is particularly noticeable at the filling opening of the garbage receptacle, and such opening has been reinforced so as to prevent the 35 walls or edges from chipping, cracking and breaking when subjected to blows.

Second, since such receptacles are ordinarily located in the rear end of a yard and project through the fence into an alley, the 40 protruding end of the receptacle is often struck by vehicles and subjected to rough usage, therefore the protruding end of the receptacle has been made of greater strength than the inner end thereof and is now 45 designed to remain in use for a considerable period of time compared to concrete garbage receptacles heretofore used.

Third, the garbage receptacle is provided with a drain opening which permits of garbage drying out in the receptacle so as to 50 be easily handled, and the drain opening permits of a sewer connection or suitable connections so that the interior of the receptacle may be flushed and maintained in 55 a sanitary condition.

Fourth, the hardware used in connection

with the concrete receptacle is of special design so as to make the receptacle water and insect tight, and these and other improvements will be hereinafter more fully 60 considered and then claimed.

Reference will now be had to the drawing, wherein—

Figure 1 is a longitudinal sectional view 65 of the concrete garbage receptacle;

Fig. 2 is a perspective view of the lower portion thereof;

Fig. 3 is a detail sectional view showing a drain opening, and

Fig. 4 is a perspective view of the con- 70 crete receptacle.

The garbage receptacle is made of concrete or other plastic material and comprises an inner vertical wall 1, parallel side walls 2 and 3, and a bottom wall 4, all of these 75 walls being formed integral and of uniform thickness throughout, with the exception of the outer edge of the bottom wall 4, which is disposed at an angle, as at 5, and its inner or upper face scooped out, as at 6, so as to 80 form a liquid shedding ledge at the outer end of the bottom wall. This liquid shedding edge serves as an end abutment, prevents liquid garbage from flowing out of the outer end of the receptacle, and permits 85 of a shovel or other implement being readily used for removing garbage from the interior of the receptacle.

The outer ends of the walls 2 and 3 and the edge of the angular ledge of the bottom 90 wall 4 have inclined faces 7 and 8 with intermediate horizontal shoulders 9. Anchored in the inclined faces 8 and the upper faces of the walls 1, 2 and 3 are bolts 10 which have the screwthreaded ends thereof 95 protruding from the faces 8 and the upper edges of the wall, as best shown in Fig. 2.

The upper portion of the garbage receptacle is in the form of a concrete cover 11 having an angularly disposed front wall 12 100 which is mounted on the shoulders 9 and the faces 8 of the walls 2 and 3 with the cover 11 forming the top of the receptacle. The cover 11 and the front wall 12 are made of two parts with the front wall 12 of 105 greater thickness than the other wall of the receptacle, and said front wall coöperates with the inclined faces 7 in forming a rectangular outer doorway for the receptacle. The cover 11 and the front wall 12 are 110 provided with openings 13 to receive bolts 10 and the threaded ends of said bolts extend

into recesses 14 in the cover and front wall to permit of nuts 15 being screwed on the bolts, the recesses 14 being then filled with concrete 17 or a suitable filler, as shown in Fig. 4.

Suitably connected to the lower outer edge of the front wall 12, preferably by hinges 18, is a drop lid 19 having its upper edge set in the doorway of the receptacle and its lower edge overlapping the doorway and extending onto the inclined face of the bottom wall ledge to frictionally engage a resilient member 20 serving as a hold-fast device for retaining the lid 19 closed. A handle 21 on the lid permits of its being raised and swung against the inclined front wall 12, to remain open while garbage is removed through the outer doorway of the receptacle. The constructive arrangement of the lid 19 prevents water or other liquid from draining into the receptacle through the outer doorway thereof and it is practically impossible for insects to crawl under the closed lid into the receptacle.

The cover 11, adjacent its inner end, has a filling opening 22 with its walls reinforced by an annular rib 23 on the inner face of the cover 11. The outer end of the filling opening 22 is reinforced by an annular metallic member 24 set in the cover and suitably anchored relative thereto, so that the annular metallic member will prevent the edges of the opening walls being chipped or broken when subjected to blows of receptacles to be emptied.

Connected to the cover by hinges 25 is a lid 26 and said lid has its outer wall provided with a handle 27 and its inner wall with a detachable container 28 for a suitable deodorant or disinfectant.

The side wall 2 at its juncture with the walls 1 and 4 has a drain opening 29 formed by setting a sleeve in the wall 2, as best shown in Fig. 3. The sleeve has its wall screw-threaded so as to receive a detachable plug 30 for closing the opening 29 and when the plug is removed the receptacle may be drained or connected to a sewer to permit of the interior of the garbage receptacle being flushed and thoroughly cleaned. At the inner end of the opening 29 there is a plate 31 provided with channel guides 32 for a strainer 33, said strainer having a suitable handle 34 which permits of the strainer being raised and lowered. This strainer is adapted to prevent solid or bulky matter from being drained from the garbage receptacle and is adapted to be raised when

the receptacle is to be flushed and cleaned. With the plug 30 removed and the strainer 60 lowered, it is obvious that the receptacle may be set at a slight inclination so that liquid matter will drain through the opening 29, thus permitting garbage within the receptacle to dry out and remain in such condition 65 as to be readily removed from the outer doorway of the receptacle.

Garbage receptacles in accordance with my invention have been constantly used and it is such improvements herein outlined 70 which have placed the receptacles on a practical and commercial basis, and it is thought the utility of the improvements will be apparent without further description.

What I claim is:—

1. A garbage receptacle having a rear wall, a bottom wall provided with an inclined ledge, side walls provided with inclined faces and horizontal shoulders, a cover mounted on the upper edges of said side and rear walls, and provided with a filling opening, a lid for such opening, a front wall mounted on the shoulders of said side walls and coöperating therewith and the ledge of said bottom wall in forming a doorway, and a lid for the doorway.

2. A garbage receptacle as characterized in claim 1, wherein the cover and front wall are held in place by bolts anchored in the side and rear walls with nuts on said bolts 90 and disposed in recesses in said cover and front wall with the recesses closed by fillers.

3. A garbage receptacle having a rear wall, a bottom wall provided with an inclined ledge, side walls provided with inclined faces and horizontal shoulders, a cover mounted on the upper edges of said side and rear walls, and provided with a filling opening, a lid for such opening, a front wall mounted on the shoulders of said side walls and coöperating therewith and the ledge of said bottom wall in forming a doorway, a lid for the doorway, one of said side walls having a drain opening adjacent the rear and bottom walls, an adjustable 105 strainer carried by said side wall for the inner end of said drain opening, and a plug for closing the outer end of the drain opening of said side wall.

In testimony whereof I affix my signature in the presence of two witnesses.

JOSEPH P. URBAN.
